(57) **CLAIM**

The ornamental design for an anti-wrinkle appliance as shown and described.

DESCRIPTION

The patent or application file contains at least one drawing executed in color. Copies of this patent or patent application publication with color drawing(s) will be provided by the Office upon request and payment of the necessary fee.

9.1 is a back perspective view of an anti-wrinkle appliance showing our new design;

9.2 is a right side view thereof;

9.3 is a left side view thereof;

9.4 is a front perspective view thereof;

9.5 is a front view thereof;

9.6 is a back view thereof;

(Continued)

9.7 is a top view thereof;
9.8 is a bottom view thereof;
9.9 is a bottom front perspective view thereof;
9.10 is a bottom back perspective view thereof;
9.11 is a right front perspective view thereof;
9.12 is a right back perspective view thereof;
10.1 is a right side view of an anti-wrinkle appliance showing our new design;
10.2 is a front perspective view thereof;
10.3 is a top view thereof;
10.4 is a left side view thereof;
10.5 is a back view thereof;
10.6 is a front view thereof;
10.7 is a back perspective view thereof;
10.8 is a bottom back perspective view thereof;
10.9 is a bottom view thereof;
10.10 is a bottom front perspective view thereof;
10.11 is a right front perspective view thereof;
10.12 is a right back perspective view thereof.
 The title of the product incorporating the design is "anti-wrinkle appliance".
